UNITED STATES PATENT OFFICE.

GEORGE S. EMERY, OF BIRMINGHAM, ALABAMA.

STATION-INDICATOR.

1,094,783.

Specification of Letters Patent.

Patented Apr. 28, 1914.

Application filed March 27, 1913. Serial No. 757,132.

To all whom it may concern:

Be it known that I, GEORGE S. EMERY, a citizen of the United States of America, and a resident of Birmingham, in the county of Jefferson and State of Alabama, have made certain new and useful Improvements in Station-Indicators, of which the following is a specification.

My invention relates to station indicators, 10 and more particularly to station indicators of the kind carried by street cars for the purpose of indicating, to passengers within the cars, the various streets as they are reached in a predetermined order of succession.

Reference is made to the accompanying drawings forming a part of this specification, and in which like letters indicate like parts.

20 Figure 1 is a fragmentary side elevation of a car provided with my improved station indicator, certain parts being broken away. Fig. 2 is a fragmentary section substantially on the line 2—2 of Fig. 10, looking in the direction of the arrow and showing a part of the ratchet mechanism used in connection with the actuating mechanism for the indicator. Fig. 3 is a detail showing in plan, a brake spring for securing a 25 positive step by step stoppage of the actuating mechanism. Fig. 4 is a side elevation of the device shown in Fig. 3. Fig. 5 is a detail showing a pair of ratchet wheels forming a part of the actuating mechanism 30 and adapted to be driven in opposite directions. Fig. 6 is a side elevation of the indicator and the actuating mechanism therefor. Fig. 7 is a detail showing, partly in elevation and partly in section, one of the 35 tension rollers for carrying the display web over the driving belt. Fig. 8 is a detail showing a magnetic trip for use in connection with the actuating mechanism. Fig. 9 is a detail showing a spring trip which may 40 also be used with the actuating mechanism. Fig. 10 is a front elevation of the indicator and actuating mechanism for the same.

Fig. 11 is a detail showing a spring-mounted disk forming a part of the gearing of the 45 actuating mechanism. Fig. 12 is a side elevation of the indicator showing the same as it would appear to an observer standing at the right of Fig. 10. Fig. 13 is a side elevation of the swinging block and parts immediately associated therewith forming a part 50 of the actuating mechanism. Fig. 14 is a

detail showing one of the rocking disks forming a part of the actuating mechanism. Fig. 15 is an elevation showing the swinging block and cams carrying the same, these 60 parts being removed from the actuating mechanism. Fig. 16 is a side view of the device shown in Fig. 15.

A car body is shown at 17 and is mounted upon wheels 18 which rest upon rails 19, 65 these parts being of the usual or any desired construction. Located at intervals along the track, and disposed midway between the rails are stationary lugs 20 extending upwardly and serving as trip members. The 70 indicator frame is shown at 21 and contains mechanism of the indicator, as hereinafter described. A revoluble shaft 22 is connected with the indicator and extends downwardly therefrom nearly to the level of the track. 75

A block 23 forming a part of the actuating mechanism for the indicator is supported, together with other parts, by a plate 24, the latter being secured to a truck 25 which is mounted upon the underside of the car. 80 The block 23 is so located that its path of travel due to the ordinary motion of the car is obstructed by the tripping member 20. The indicator frame 21 is provided with spacing rods 26 whereby it is held together. 85

I provide four rollers 27, 28, 29, 30, which are mounted rigidly upon revoluble shafts 30^a, 30^b, 30^c, 30^d, the latter extending entirely through the frame-work. Engaging these rollers is a motor ribbon 31 which is of 90 a width commensurate with the length of the rollers and is endless, as indicated by dotted lines in Fig. 6. An idle roller 32 engages the motor ribbon 31 and is provided with axial pins 33 which extend through 95 slots 34 in the frame-work, the slots being inclined as indicated in Fig. 6. The weight of the idle roller keeps it in engagement with the motor ribbon and thus tends to render the tension of the ribbon substantially constant. 100

The frame is provided with slots 35, 36, which, like the slot 34, are slightly inclined. Extending through the slots 35, 36 are two tension rollers of the type shown more particularly in Fig. 7. Each of these rollers is provided with a shaft 37 upon which is rigidly mounted a cylinder 38. A spiral spring 39 encircles this cylinder and is connected at one end with a barrel 40 having a 105 general cylindrical form and provided with heads 40^a. The opposite end of the spring

39 is secured directly to the cylinder 38. Set collars 43, 44 are secured rigidly upon the shaft 37 and are provided with pins 41, 42. When the roller is mounted in position the 5 shaft 37 is extended across the frame and lodged in the slots 35 or 36, as the case may be, the pin 41 or 42 being brought into the position indicated in Fig. 6. By this means the shafts 37, 38 are prevented from turning relatively to the framework, though the barrels 40 can turn.

The two rollers just mentioned are exactly alike as to construction, and are interchangeable, but when used together as a 15 pair, as indicated at the left of Fig. 6, the pin 41 of one roller extends in the same direction as the pin 42 of the other roller. This is done for the reason that when one of the rollers is winding its spring 39, the 20 spring of the other roller is unwinding; both rollers being thus kept constantly under tension. I therefore conveniently designate the two rollers as tension rollers. Each of them is provided with ball bearings 45. A 25 display web is shown at 46 and has generally the form of a long strip which is partially wound upon each of the two rollers just described, and shown at the left of Fig. 6. The display web 46 is provided with the 30 names of streets, interspersed if desired with advertisements, and engages and partially encircles the motor ribbon 31, being supported along with this ribbon by the rollers 27, 28, 29, 30. The vertical shaft 22 is 35 mounted in bearings 47, 47^a, 47^b, and is provided with two bevel pinions 48, 49 which are mounted loosely upon it. The bevel pinions are provided with clutch members 50, 51. A clutch collar 52 is provided with clutch members mating the 40 clutch members 50, 51, and is splined upon the shaft 22 and revoluble with it. Engaging the clutch collar 52 is a clutch fork 53^a which is integral with lever 53, this lever 45 being rigidly mounted upon a shaft 54. By swinging the lever 53 to the right according to Fig. 6, the bevel pinion 48 is caused to turn with the shaft 22, whereas by swinging the lever 53 to the left according to 50 this figure, the pinion 48 is rendered idle and the pinion 49 turns with the shaft 22. Meshing with the bevel pinions 48, 49, is a bevel gear 50^a which is mounted rigidly upon a shaft 55, the latter extending through 55 the frame.

Mounted rigidly upon the shaft 55 and revoluble therewith, is a large gear wheel 56 shown more particularly in Fig. 12. This gear wheel carries a number of pins 57 60 and mounted upon these pins are rollers 58. Meshing with the gear wheel 56 are four pinions 59, 60, 61, 62, the latter being rigidly mounted upon the respective shafts 30^a, 30^b, 30^c, 30^d, and carrying the rollers 65 27, 28, 29, 30. A lever 63 (see Fig. 12) is

pivotedly mounted upon a pin 65 and is provided with a boss 64 adapted for engagement with two rollers 58. A spring 66 is connected with the lever 63 and with the frame work. A dash pot 67 is also connected with the lever 63 and is disposed adjacent to the spring 66. The spring 66, by its tension, draws the lever 63 downwardly so that the boss 64 lodges between the two adjacent rollers 58. In this manner, when the gear wheel 56 is turned step by step, as hereinafter described, the lever 63 by its action upon the rollers 58, causes the gear wheel 56 to stop in definite successive positions,—or in other words, its 75 step by step motion is rendered positive.

Secured upon the car body is a bracket 68 (see lower left hand corner of Fig. 10) which serves as a bearing for the lower portion of the shaft 22. Mounted rigidly upon this shaft is a bevel pinion 69 which meshes with a bevel gear 70. This bevel gear is mounted rigidly upon a shaft section 71, the latter being connected by a coupling 72 with another shaft section 73, the latter being flexible and connected by another coupling 74 with a shaft section 75. This shaft section 75 carries a pin 76 which extends through a slot 76^a in a hub 77. A disk 78 carries this hub and also carries two pins 79 which extend to the right according to Fig. 10. Connected with each pin 79 are two spiral springs 80, these springs being also connected with two pins 81 which are carried by another disk 82. This disk is provided 95 peripherally with notches 83. A leaf spring 84 is mounted upon a bracket 85 and by aid of screws 83^a and pins 83^b, is adjustable. That is to say, the tension of the spring may be adjusted so that the spring bears hard or 100 otherwise upon the disk 82 and its grip within the notches 83 may thus be regulated to some extent at the will of the operator.

The disk 82 is mounted rigidly upon a shaft 86 which is journaled within the 110 bracket 45 and is provided with set collars 87 to prevent longitudinal movement of the shaft relatively to the bracket. Two cams 88, 89, are each provided with an opening 89^a, and fitted loosely upon the shaft 86. 115 These cams are provided with notches 90, 91 and are secured to the block 23. The cams are located upon opposite sides of the block and also extend in opposite directions, as will be understood from Fig. 15.

Two rocking plates 92, 93 are journaled loosely upon the shaft 86. The disk 92 carries a pin 94 and the disk 93 carries a pin 95. The disks 92, 93 are reversed relatively to each other—that is, they have their similar 125 faces toward each other and are adapted to rock in opposite directions, but are otherwise alike. Each disk 92, 93, carries a pawl 96 and this pawl carries a pin 98 extending laterally from it. At the outer or free 130

end of each pin 98 is secured a spiral spring 99, this spring being also connected to a pin 100, carried by the other disk. That is, each spring 99 is secured at one of its ends to a 5 pin extending from a pawl carried by one disk, say 92, but the other end of the stem spring is secured to a pin carried by the other disk, say 93. Adjacent to each pawl 96 and bearing upon the same, is a leaf 10 10 spring 97 for the purpose of tightening the pawl. The springs 99 are employed to retract the disks 92, 93 and bring them back to their respective normal positions. Mounted rigidly upon the shaft 86 are two 15 ratchet wheels 101, 102, these ratchet wheels being located between the disks 92, 93. Each pin 98 extends in close proximity to the adjacent cam 88 or 89, so that when the block 23, carrying the cams, is rocked it causes one 20 of the cams 88 or 89 to momentarily raise the adjacent pin 98, and thus momentarily lift the particular pawl carrying the pin out of engagement with the ratchet wheel upon which it normally rests. At the instant this 25 occurs, the opposite cam (88 or 89) by moving against the adjacent pin 94 or 95 rocks the disk carrying this pin. The pawl 96, carried by this disk, thereupon turns the ratchet wheel which it engages. Thus when 30 the car travels in either of two directions, or rather when the block 23 is tripped in either of two directions, one of the pawls 96 is practically idle so as to prevent retrograde rotation of the ratchet wheels 101—102, or 35 the shaft supporting them.

In Figs. 8 and 9 I show two special forms of tripping devices, each having the same general purpose as the lugs 20. Referring more particularly to Fig. 9, a ground plate 40 is shown at 103 and extending through a hole in this ground plate is a tripper 104 which is pressed upwardly by a spring 105. This construction offers an advantage in that if a wagon or the like should throw a 45 considerable weight upon the tripper 104, the latter is free to yield and move downwardly without causing any jolt to the wagon or any injury to the tripper. In Fig. 8 the tripper 106 is loose relatively to the 50 ground plate and normally rests upon a support 108 located below the ground plate. A magnet 107 carried by the car draws the tripper 106 upwardly, as soon as the car reaches such position that the magnet 107 55 is directly over the tripper. For this purpose the tripper 106 should be made of iron or other magnetic material.

Mounted rigidly upon the shaft 54 and located within the indicator frame is a lever 109 provided with a downwardly extending portion 110. Two tripping fingers 111, 112, are mounted directly upon the display web 46 so as to overhang one of the adjacent edges thereof, these tripping fingers 60 being located comparatively near the ends

of the web. They are so shaped as not to interfere with the winding of the web upon the barrels 40, and for this purpose they extend laterally from the web in a direction crossing the plane thereof. The tripping 70 finger 111 is so located and disposed that when the web is nearly unwound from the adjacent or upper barrel 40, the tripping finger 111 is brought into engagement with the upper end of the lever 109. The tripping finger 112 is so disposed that when the web 46 is nearly unwound from the lower barrel 40, the tripping finger in question is brought against the lower portion 110 of the lever just mentioned, so as to shift this lever 75 into its reverse position. The lever 109 is provided with a weight 113 for the purpose of normally maintaining it off its center, so that when the upper end of the lever is thrown to the right or the left, according to 80 Fig. 17, the weight will hold the lever in the position which it thus assumes.

The trippers shown in Figs. 8 and 9 are preferable where my device is used in a city, but in the country or on suburban lines I 90 prefer to use the lug 20 on account of its cheapness.

The operation of my device is as follows:—The parts being assembled and arranged as above described as the car proceeds upon the track, or in the direction indicated by the arrow in Fig. 1. The block 23 is periodically brought against the lug 20 or analogous tripping member 104 or 106, shown in Figs. 8 and 9 respectively. Each 95 time the block 23 strikes against a tripping member, the block is swung upon the shaft 86 in a direction which according to Fig. 1 would be clockwise. The notch 90 of the cam 88 (see Fig. 15) engages the pin 95, 100 carried by the disk 93 and causes this disk to rock in a clockwise direction according to Figs. 1, 2 and 14. The pawl 96 carried by this cam thereupon turns the ratchet wheel 102 in a clockwise direction for a distance 105 corresponding to the length of one tooth of the ratchet wheel. The shaft 86 is thus turned step by step and through the disk 82, springs 80, disk 78 and flexible shaft sections turned thereby, motion is communicated to the bevel gear 70. This turns the bevel gear 69 and rotates the shaft 22. Motion is communicated through the bevel pinion 48 or the bevel pinion 49, depending 110 upon the position of the clutch collar 52, 115 this in turn depending upon the position of the lever 53 for controlling the clutch mechanism. If, however, the car is traveling in the opposite direction—that is, to the left according to Fig. 1,—the shaft 86 is 120 turned step by step in a counterclockwise direction according to Fig. 1. In this event the swinging block 23 engages the lug 20 or other tripping member, and is rocking in a counterclockwise direction according to Fig. 125 130

15. The notch or shoulder 91 of the cam 89 lodges against the pin 94 carried by the disk 92, whereupon this disk is rocked upon the shaft 86, and the pawl 96 carried by the disk 92 now engages the ratchet wheel 101, thus conferring a step by step movement upon the shaft 86 and parts controllable thereby. It will thus be seen that whether the car be traveling forward or backward, the bevel gear 51^a is turned accordingly. This gear, acting through the shaft 55, causes the large gear 56 to turn and the rotation of this gear turns various gear pinions 59, 60, 61, 62, carrying the rollers 27, 28, 29, 30. The motor ribbon 31 carried by these rollers and tensioned by the idle roller 32 is thus moved step by step, and as it travels it carries with it the web 46 provided with the names of the streets or stations or with advertising matter as desired. As the strip last mentioned is wound off of one of the barrels 40 (see Fig. 7) it is wound upon the other, this action being automatic as above described and due to tension of the springs 39. Upon reaching the end of the route the car may start directly backward or may pass around a loop and thus virtually continue to travel forward. If the car merely backs over the route which it has just traveled, no change is necessary in the position of the lever 53. If, however, the end of the route terminates in a loop the tripping finger 111 is brought into engagement with the upper portion of the lever 109, or the tripping finger 112 is brought against the lower portion 110 of this lever, as the case may be. In either event the lever is rocked and is held in its new position by the weight 113, as above described. This movement rocks the shaft 54 and causes the clutch fork 53^a to shift the clutch collar 52, thereby reversing the direction of travel of the web 46 and parts immediately associated with it. If for any reason the operator desires to reverse the travel of the web 46 relatively to the travel of the car at any time or at any point of travel along the route, he does this by merely shifting the lever 53 by hand.

It will be noted that the gearing as a whole is somewhat flexible owing to the action of the springs 80 and the use of a flexible shaft section, so that no undue strain is

thrown upon any part of the gearing in consequence of shocks or irregularities in movements of the actuating mechanism. It will also be noted that the step-by-step movement of the various parts is rendered positive and accurate.

I do not limit myself to the precise arrangement shown, as variations may be made in the mechanism without departing from the spirit of my invention, the scope of which is commensurate with my claims.

The indicator is preferably placed at the ends of the car, inside, and over door entrances.

I claim:—

1. A station indicator comprising a revoluble shaft, means controllable by movements of a car for turning said shaft step by step, a flexible shaft section, spring mechanism connecting said first mentioned shaft section with said flexible shaft section, an indicator, a gearing connecting said flexible shaft section with said indicator. 75

2. A motor mechanism for indicators comprising a revoluble shaft, a pair of cams connected together and mounted loosely upon said revoluble shaft, said cams as a unit being free to swing in two directions, means controllable by the travel of a car for swinging said cams relatively to said shaft, a pair of disks each mounted loosely upon said shaft and each disposed adjacent one of said cams, a pin carried by each disk and disposed partially within the path of travel of the adjacent cam, in order to enable each cam when rocked in one direction to rock one of said disks in the same direction, a pair of pawls each carried by one of said disks, said pawls extending in opposite rotary directions, a pair of ratchet wheels mounted rigidly upon said shaft, each ratchet wheel mating one of said pawls and being arranged to turn the shaft in one direction, and mechanism controllable by the swinging of said cams in either direction for throwing one of said pawls out of engagement with its mating ratchet. 95
